UNITED STATES PATENT OFFICE.

JOHN J. DUNNIGAN, OF ROCHESTER, NEW YORK.

WASHING MACHINE.

Application filed July 18, 1921. Serial No. 425,694.

To all whom it may concern:

Be it known that I, JOHN J. DUNNIGAN, a citizen of the United States, residing at Rochester, in the county of Monroe and State of New York, have invented certain new and useful Improvements in Washing Machines, of which the following is a specification.

The object of this invention is to provide 10 a new and improved type of power washing machine.

This and other objects of the invention will be fully illustrated in the drawings, described in the specification and pointed out 15 in the claims at the end thereof.

In the accompanying drawings:

Figure 1 is a side elevation of the washing machine.

Figure 2 is an end elevation of the washing machine.

Figure 3 is a longitudinal cross section of the machine, the section being taken on the line 3^x—3^x of Figure 4.

Figure 4 is a top plan view of the machine.

Figure 5 is a side elevation of the machine with a modified form of driving mechanism.

Figure 6 is a detail sectional view of the gear shift for the wringer of the washing machine.

Figure 7 is a detail perspective view of one of the frames forming part of each of the ends of the clothes receptacle of the washing machine.

25 In the several figures of the drawings, like reference numerals indicate like parts.

In the drawings, reference numeral 1 indicates the frame of the machine which is preferably rectangular in outline and is 30 suitably supported on the legs 2, 3, 4 and 5. The frame 1 supports the semi-circular tub 6 at the top thereof with the clothes receptacle 7 mounted to oscillate or rotate therein. For this purpose the clothes receptacle 7

45 is suspended on the shaft 8 which shaft is mounted in suitable bearings provided on each side of the frame 1. Keyed to the shaft 8 at the outer end thereof is a sprocket 9 which is driven by the sprocket chain 10 from the sprocket gear 11. The sprocket gear 11 is mounted on the stud 12 provided on one side of the frame of the machine. The sprocket gear 11 is given an oscillating motion by the crank disc 13 by means of the 50 connecting rod 14 which connects the

sprocket with the crank disc. The crank disc 13 is keyed to the outer end of the shaft 15 and is driven by the electric motor 16 through the train of gearing comprising the pinion 17 and gear 18, the gear 18 being keyed to the shaft 15 and the pinion 17 being keyed to the armature shaft of the electric motor 16. Provided on the shaft 15 at a point between the crank disc 13 and gear 18 is a clutch 19. This clutch is operated by the lever 20 and can be operated to either connect or disconnect the crank disc 13 from the gear 18 so that the crank disc may remain idle while the electric motor 16 continues to drive the driving mechanism of the wringer that will hereinafter be described. For this purpose the shaft 15 is divided by the clutch 19 so that the crank disc 13 is only rotated when both of the members of the clutch have been brought 65 into engagement with each other.

Keyed to the shaft 15 at the end opposite to the crank disc is the bevel pinion 21. This pinion is adapted to mesh with the bevel pinion 22 carried on the vertical shaft 23. The shaft 23 is mounted in bearings provided in the brackets 24 and 25 and has a pair of bevel pinions 26 and 27 keyed thereto near the top thereof.

Mounted to swing on the upper end of the 70 vertical shaft 23 is the bracket 28. This bracket is provided with suitable bearings in which the shaft 29 is mounted to rotate. The shaft 29 has the bevel pinion 30 keyed to the end thereof which pinion is adapted 75 to mesh with either the pinion 26 or the pinion 27 carried on the shaft 23. For the purpose of bringing the pinion 30 into mesh with the pinion 26 or pinion 27 the bracket 28 is adapted to be raised or lowered on the 80 shaft 23. This is accomplished by means of the cam lever 31 which is mounted to rock between the lugs 32 and 33 carried at the top of the bracket 28.

The cam lever 31 is provided with the cam 85 surface 34 which normally rests on the shoulder 35 provided at the upper end of the shaft 23. On the movement of the cam lever 31 to the left the cam surface 34 operates to raise the bracket 28 on which it is mounted 90 and in doing so moves the pinion 30 out of mesh with the pinion 26 and brings it into mesh with the pinion 27, the reverse being 95 true when the movement of the lever 31 is from the left to the right. In this way the 100

shaft 29 on which the pinion 30 is keyed is rotated at will in either one or the other direction.

Supported by the bracket 28 is the wringer 5 frame 36 which may be any one of the well known types of wringers, the shaft 29 operating to rotate the lower roll 37 for the purpose of driving the wringer.

When it is desired to disconnect the 10 wringer from the driving mechanism of the clothes receptacle, the lever 38 is operated to raise the pinion 22 and move the teeth thereof out of mesh with the teeth of the pinion 21. In this way both the driving 15 mechanism for the clothes receptacle as well as the driving mechanism for the wringer may be independently or jointly driven by the motor 16.

The clothes receptacle 7 comprises a shell 20 having a curved and closed bottom conforming with the curved bottom of the tub 6. The bottom is made up of slats of wood which are tied together by the ends 39 and 40. These ends are preferably made up as 25 a casting in the form of a segment as shown in Figure 7 with the openings filled out with wooden slats in order to close the ends and make them as light as possible and still retain the necessary strength therefor. The 30 casting comprising each of the ends of the clothes receptacle is provided with an inwardly projecting flange 40^A at the bottom and with a guide 40^B formed by a channel at each end thereof. The flange 40^A at the 35 bottom is adapted to support the bottom slats of the clothes receptacle and the guides 40^B at the ends are adapted to receive the gate that closes each side of the clothes receptacle as will be described.

40 The sides of the clothes receptacle are closed by a pair of gates 41 and 42. These gates are each made up of a suitable framework with a handle 43 formed at the top thereof by means of which the gate may be 45 inserted between the guides provided on the edges of the ends and made to rest on the inwardly projecting flanges at the bottom of the ends.

The frame is covered by a wire mesh or 50 screen that permits the water entering and discharging from the clothes receptacle during its oscillation in the tub 6.

On the rotation of the shaft 15 the crank disc is rotated and this causes the connecting 55 rod 14 to oscillate the sprocket gear 11. This oscillating motion of the sprocket gear in turn is transmitted by the sprocket chain 10 to the sprocket gear 9 mounted on the shaft 8. The rocking motion given to the shaft 8 60 in turn oscillates the clothes receptacle 7.

The clothes that are contained in the clothes receptacle are thus swished through the water contained in the tub in the clothes receptacle as the clothes receptacle swings 65 back and forth. The clothes are also tum-

bled over the bottom thereof while the force of the water entering the gates of the clothes receptacle operate to thoroughly clean them.

For the purpose of giving the clothes a rubbing action as they tumble in the closed 70 bottom of the clothes receptacle, cross slats 45, 46 and 47 are provided thereon. Of these slats the intermediate slat is much larger than each of the other slats and series of smaller slats 48 are provided on each side 75 thereof. The clothes in tumbling over this slat are thus given a more thorough rubbing than is the case in tumbling over the outer slats. Each of the slats is preferably made triangular in cross section as indicated in 80 Figure 3.

In addition to the cross slats on the bottom of the clothes receptacle each of the ends thereof is provided on the inside with similar slats 48 in order to provide a rubbing 85 action of the clothes at the sides of the clothes receptacle as well as the bottom thereof.

As will be seen from an inspection of the figures the cover of the tub 6 is made up in 90 the form of a duplicate tub 49 which is mounted in the rectangular frame 50 hinged to one end of the frame 1. The frame 50 is adapted to be swung on hinges from the position shown in Figure 1 to the position 95 shown in Figures 3 and 4 in which the cover 49 serves as a second tub into which the clothes can be wrung from the tub 6. In order to properly support the second tub on the frame work of the first tub a pair of legs 100 51 are hinged to one end of the rectangular frame 50. These legs are placed on top of the frame 50 when the tub is used as a cover for the tub 6 as shown in Figure 1 but are swung down and reinforced by suitable 105 braces 52 when the tub 6 is opened and the tub 49 is placed in the position shown in Figure 3.

The wringer 36 is adapted to be swung on the shaft 23 and can be held in place in different positions with relation to the tubs 6 and 49. Thus the wringer may be swung from the full line position illustrated in Figure 2 to the dotted line position indicated thereon for the purpose of wringing the 115 cloth from the tub 6 into the tub 49. The wringer is locked in this position by means of the locking pin 53. This pin passes through the lug 54 provided on the bracket 28 and through a similar lug 55 provided in 120 the bottom of this same bracket into an opening in the bracket 24.

A spring 56 is placed between the collar 57 mounted on said locking pin, and the under side of the lug 54. The expansion of 125 this spring holds the locking pin in place in the bracket 24 from which it can only be disengaged by lifting the pin by means of the handle or knob 58 against the action of the spring 56.

Instead of giving the clothes receptacle 7 an oscillating motion by means of the crank disc and sprocket gearing the clothes receptacle may be continuously rotated by 5 means of the train of gearing shown in Figure 5. A small pinion 60 is substituted for the crank disc 13 and the rotation of this pinion is transmitted to the drum by means of the gears 61 and 62.

10 I claim:

1. A power washing machine comprising a frame, a tub rigidly supported in said frame, a clothes receptacle mounted to oscillate in said tub, said receptacle comprising 15 a pair of ends having a curved bottom and radial edges, an inwardly projecting curved flange formed at the bottom of each of said ends, channel guides formed on each of the radial edges of said ends, a bottom support- 20 ed between said ends on top of said curved flanges, gates adapted to slidably engage the channel guides, said gates being removable to permit the insertion of the clothes into said receptacle.

25 2. In a power washing machine, the combination of a frame, a stationary tub supported by said frame, a clothes receptacle mounted to oscillate in said stationary tub, said clothes receptacle being made up of a 30 pair of segmental ends, an inwardly projecting flange being formed on the curved side of each of said ends, a guide channel formed on each of the radial edges of said ends, the guide channels of one of said ends

being parallel to the guide channels of the 35 other of said ends and the grooves of said channels facing each other, gates adapted to slide in said guide channels to form the sides of said receptacle, a handle formed at the top of each of said gates with which said gates 40 can be withdrawn to allow the insertion of the clothes into said receptacle.

3. In a power washing machine, the combination of a frame, a stationary tub supported by said frame, a clothes receptacle 45 mounted to oscillate in said stationary tub, said clothes receptacle being made up of a pair of segmental ends, an inwardly projecting flange being formed on the curved side of each of said ends, a guide channel 50 formed on each of the radial edges of said ends, the guide channels of one of said ends being parallel to the guide channels of the other of said ends and the grooves of said channels facing each other, gates adapted 55 to slide in said guide channels to form the sides of said receptacle, a handle formed at the top of each of said gates with which said gates can be withdrawn to allow the insertion 60 of the clothes into said receptacle, 65 transverse bars mounted in the bottom of said receptacle, and radial bars mounted on the inside of said ends, all of said bars being adapted to rub the clothes in said receptacle during the oscillation thereof.

In testimony whereof I affix my signature.

JOHN J. DUNNIGAN.
